UNITED STATES PATENT OFFICE

2,259,416

LAMP CONSTRUCTION

Paul Norris Gardner, Bethesda, Md., assignor to
Mer-Q-Ree Incorporated, Bethesda, Md., a corporation of Maryland

Application December 19, 1940, Serial No. 370,872

6 Claims. (Cl. 240—2.25)

This invention relates to luminous devices, and is concerned with the provision of improved lamp structures of the type wherein a fluorescent or phosphorescent coating carried by an outwardly visible member thereof may be rendered luminous by excitation by light from a primary source of light contained within, or carried by, the lamp structure.

Luminous lamp devices of the type above referred to are broadly old, having been described in, among others, the Dodds Patents Nos. 1,275,871, 1,275,872 and 1,312,312, and are typified by a battery lamp modified by the imposition of a layer of fluorescent or luminescent material upon the glass closure or lens of the lamp. In making use of such lamps, the electric circuit when closed lights an incandescent lamp bulb and the light from the latter excites or activates the fluorescent material causing the same to glow. Such excitation of the fluorescent material need continue for only a matter of a minute (more or less), whereafter the electric current may be broken, while the fluorescent material continues to glow for a matter of two to four hours. When the fluorescence of the material diminishes the fluorescent material may be re-excited by brief exposure to light from the electric lamp.

However, for "blackout" purposes, the necessary lighting of the electric lamp for re-exciting the fluorescent material creates a disadvantage, in that during its actuation the latter yields real illumination which is undesirable.

An object of the present invention is the provision of an improved luminous device, of the general type above described, so constructed that during the period (or periods) of excitation of the fluorescent material by the primary light sources, the source of excitation is hooded so that no light therefrom escapes from the device.

Another object of the invention is the provision of a hood and of hood-actuating means cooperating with the luminous device to prevent energization of the primary light source for excitation of the fluorescent material when the hood is in retracted position. Yet another inventive object is to provide a luminous device whose circuit-closing and opening means functions to close and open an opaque diaphragm located in front of the fluorescent material-carrying member of the device.

These, and other, objects and novel features of the invention will be more fully disclosed by the following description and the accompanying drawing, in which

Figure 1 is a side elevation, partly in section, of a flashlamp embodying the invention,

Figure 2 is an end view thereof,

Figure 3 is a fragmentary side elevation of a modified form of the invention,

Figure 4 is an end view thereof,

Figure 5 is a fragmentary side elevation of another modification,

Figure 6 is an end view thereof, and

Figure 7 is a diagrammatic view illustrating a further modification.

Referring to Figs. 1 and 2, 10 indicates a battery operated flashlamp including an incandescent lamp bulb 11 mounted in the end 12 of the casing within a reflector 13. A flanged clamping ring 14 threaded on the casing part 12 secures a transparent lens plate or cover glass 15 in position in front of the reflector 13 and bulb 11.

A layer of fluorescent or phosphorescent material 16 is carried on the inner surface of the lens plate 15 so that it will be visible through the plate 15 and positioned to be activated and rendered luminous upon energization of the light bulb 15 upon closing of the lamp switch 17 as will be readily understood.

For the purpose of preventing escape of light rays upon energization of the bulb 11, a pivoted opaque cover plate or baffle plate 18 is mounted on the ring 14. The plate 18, which is preferably made of sheet metal, is mounted on a ring 19 carried by the clamping ring 14, being pivotally secured thereto by a headed pivot pin 20 in the form of a rivet. The pivot 20 passes through the plate 18 adjacent the edge thereof so that the plate 18 may swing in its own plane to a position clear of the glass plate 15.

In using this form of the invention as a "blackout" lamp, the plate 18 is swung to the position shown over the glass plate 15 and the switch 17 is operated to energize the lamp bulb 11. The light from the bulb 11 will excite the fluorescent layer 16 but the rays therefrom will not be visible outside because the opaque plate 18 prevents emission thereof. After a brief interval, the switch 17 is operated to extinguish the lamp bulb 11 and the plate 18 is swung on its pivot to the dotted line position so that the luminous layer 16 will be visible.

Referring to the modification shown in Figs. 3 and 4, the shutter plate 118 instead of being pivoted to swing in its own plane is hinged at 120 on the carrier ring 119 mounted on the lens plate clamping ring 114. It will be understood that the reflector mounting part 112 and other

conventional parts of the lamp 110 may be the same as shown in Fig. 1.

For mounting the hinged shutter 118, a filler sector plate 121 is rigidly mounted on the ring 114 and a biasing spring 122 is associated with the hinge to bias the shutter to the dotted line open position in which the cover glass is exposed to view.

Means are provided for closing the shutter plate 118 automatically when the lamp bulb is energized to re-excite the luminous body thereon and to prevent actuation of the switch 117 to energize the bulb when the shutter is in other than closed position. This means comprises a reciprocable rod 123 extending coaxially within the casing of the lamp 110 and connected at 124 with the sliding button switch 117 of the lamp. The rod 123 extends forward from the button 117 and at its forward end 125 extends through an opening in the sector plate 121 adjacent the hinge 120 to engage a projecting shoulder 126 carried by the shutter plate 118. The shoulder 126 extends at right angles from the plate 118 at the hinge and engages the sector plate to act as a stop when the shutter swings out to the open dotted line position. When the shutter is in this position, the shoulder 126 overlies the end of the rod 123 acting as a stop to prevent shifting of the rod outwardly until the shutter is moved to the closed position.

As seen in Fig. 3, when the button switch is moved to the "on" position, shown in full lines, the end 124 of the rod in moving from a retracted position flush with the sector plate engages the shoulder 126 to swing the plate 118 to the closed light-intercepting position, before the lamp is illuminated. The end 124 then prevents opening of the shutter until the rod is retracted by moving the switch button to "off" position, whereupon the spring 122 throws the shutter 118 to open position.

In the form of the invention shown in Figs. 5 and 6, the operating rod 223 attached to the sliding button switch 217 at 224 engages at its upper end 225 in a slot 227 in an arm 228 carried by the shutter plate 218. The shutter plate in this form of the invention is also hinged at 220 on a sector plate 221 mounted on carrier ring 219. It will be obvious that as the button 217 is moved to the "on" position to light the lamp bulb, not shown, the shutter 218 will be closed automatically and when moved to "off" position to extinguish the bulb, the shutter will be opened by reason of retraction of the rod 223.

The form of the invention shown in Fig. 7 is particularly adaptable to use with lamps which are situated in a position remote from the operator, such as the head or tail lamps of a motor vehicle, or the like. In this embodiment, the lamp 310 is provided with a bulb 311 adapted to be energized by current from a battery 350 upon closure of switch 317. It is understood that this lamp is equipped with a reflector for the bulb 311 and a glass lens plate bearing a luminous coating similar to the coating 16 on the lens plate 15.

A shutter plate 318 mounted by a pivot pin 320 on the lamp casing 310 is provided with an operating arm 328 projecting from the edge thereof. The operating arm 328 is provided with a slot 327 in which is engaged the end of a reciprocable operating rod 323 actuated by a solenoid 351 connected in series with the lamp 311. The solenoid 351 is rigidly mounted on a stationary part of the lamp or support on which the

lamp is mounted and the armature rod 323 is normally projected to shutter opening position by a spring 352. It will be evident that with the parts in the dotted line position, closing of the switch 317 to energize the lamp bulb 311 will also close the circuit through the solenoid 351 to retract the armature 323 and swing the shutter 318 on the pivot 320 to the light-intercepting position over the face of the lamp, as shown in full lines.

Although preferred embodiments of the invention have been shown and described by way of illustration, it will be understood that various other modifications and changes in the details of construction and operation of the parts may be resorted to without departing from the spirit of the invention within the scope of the appended claims.

I claim:

1. A self-luminous lamp construction comprising a casing having an opening therein, an electric lamp mounted in said casing, means for mounting a body of fluorescent material in said casing visible through said opening and positioned to be activated by light from said electric lamp, switch means for controlling energization of said electric lamp, a shutter carried by said casing shiftable from and to a closed position over said opening to intercept light rays from said lamp when the latter is energized to activate said fluorescent material, and means for preventing actuation of said switch means to energize said lamp when said shutter is in other than closed position and for preventing shifting of said shutter from closed position when said lamp is energized.

2. A self-luminous lamp construction comprising a casing having an opening therein, an electric lamp mounted in said casing, means for mounting a body of fluorescent material in said casing visible through said opening and positioned to be activated by light from said electric lamp, switch means for controlling energization of said electric lamp, a shutter carried by said casing shiftable from and to a closed position over said opening to intercept light rays from said lamp, and means operable to shift said shutter to closed position over said opening upon actuation of said switch means to energize said lamp.

3. A self-luminous lamp construction comprising a casing having an opening therein, an electric lamp mounted in said casing, means for mounting a body of fluorescent material in said casing visible through said opening and positioned to be activated by light from said electric lamp, a pivoted shutter carried by said casing adapted to swing from a closed light intercepting position over said opening to an extended position free of said opening, a switch including a movable member for controlling energization of said electric lamp, and means connecting said movable member and said shutter to swing the latter to light intercepting position when said switch is actuated to energize said electric lamp.

4. A self-luminous lamp construction comprising a casing having an opening therein, an electric lamp mounted in said casing, means for mounting a body of fluorescent material in said casing visible through said opening and positioned to be activated by light from said electric lamp, a pivoted shutter carried by said casing adapted to swing from a closed light intercepting position over said opening to an extended position free of said opening, a switch including

a movable member for controlling energization of said electric lamp, and means including a link connected between said shutter and said movable member for swinging said shutter to closed position when said switch is operated to energize said electric lamp and to swing said shutter to extended position when said switch is operated to extinguish said electric lamp.

5. A self-luminous lamp construction comprising a casing having an opening therein, an electric lamp mounted in said casing, means for mounting a body of fluorescent material in said casing visible through said opening and positioned to be activated by light from said electric lamp, a pivoted shutter carried by said casing adapted to swing from a closed light intercepting position over said opening to an extended position free of said opening, an abutment carried by said shutter, spring means normally biasing said shutter to extended position, a switch including a movable member for controlling energization of said electric lamp, and a shiftable rod connected to said movable mem-

ber adapted to engage said shoulder to swing said shutter to closed position when said switch is operated to energize said electric lamp and to release said shutter when said switch is operated to extinguish said electric lamp.

10. A self-luminous lamp construction comprising a casing having an opening therein, an electric lamp mounted in said casing, means for mounting a body of fluorescent material in said casing visible through said opening and positioned to be activated by light from said electric lamp, switch means for controlling energization of said electric lamp, a shutter carried by said casing shiftable from and to a closed position over said opening to intercept light rays from said lamp, a solenoid connected in series with said electric lamp, and a connection from said solenoid to said shutter operable to shift said shutter to closed position over said opening upon actuation of said switch means to close the circuit to said lamp and solenoid.
